GUARD RAIL STRUCTURE

Filed Oct. 17, 1929

Inventor:
August Enstrom,
By myself, *August Enstrom*,
Attest,
Attest

UNITED STATES PATENT OFFICE

AUGUST ENSTROM, OF CHICAGO, ILLINOIS, ASSIGNOR TO PETTIBONE MULLIKEN COMPANY, OF CHICAGO, ILLINOIS, A CORPORATION OF DELAWARE

GUARD-RAIL STRUCTURE

Application filed October 17, 1929. Serial No. 400,296.

One of my objects is to provide a guard rail which shall be easy to install and require less time for installation than guard rails as hitherto provided.

5 Another object is to provide a guard rail structure which when installed in operative position relative to a main rail will remain in such position during the continued use of the structure.

10 Another object is to provide a guard rail structure which will eliminate the necessity of boring holes in the main rail and will avoid the use of bolts and fittings.

Another object is to provide a guard rail 15 structure of simple construction and which will be held against rotation, or canting, under the forces to which it is subjected in use.

Another object is to provide for the adjustment of the guard-rail relative to the main 20 rail, and other objects as will be manifest from the following description.

Referring to the accompanying drawing:

Figure 1 is a broken plan view of a main rail of a railway track with which is associated a guard rail embodying my invention, the structure shown constituting a guard rail and main rail assembly.

Figure 2 is a section taken at the line 2 on Fig. 1 and viewed in the direction of the arrow.

Figure 3 is a section taken at the line 3 on Fig. 1 and viewed in the direction of the arrow; and

Figure 4, a section taken at the line 4 on Fig. 2 and viewed in the direction of the arrow.

Referring to the particular assembly shown, 5 represents one of the main rails of a railway track and 6 a guard rail located 40 along one side of the main rail, the ties on which these rails are supported being represented at 7.

Certain of the ties 7 between the ends of the guard rail are shown as provided with tie plates 8 having plain upper faces, and the ties 7 therebetween are provided with plates 9 forming portions of rail braces hereinafter described, on which the main rail and guard rail are supported, these rails being spiked 50 to the ties beneath them by spikes driven

through openings in opposite ends of the plates 8 and 9 and through ends of the guard rail as hereinafter described.

The guard rail 6 which may be formed of a section of railway rail comprises a body portion 10 which extends lengthwise of the main rail 5 and in spaced relation thereto as shown to accommodate the flanges of the wheels traveling over the track. The end portions of the body 10 of the guard rail diverge outwardly in opposite directions as shown at 11 and 12 and its terminal portions represented at 13 are relatively thin, compared with the height of the body portion 10 of the guard rail, and project laterally in the same direction from said body portion, to extend beneath and slightly beyond, the main rail 5, the portions 13 of the guard rail being recessed at their upper faces as represented at 14 to receive the main rail 5 which thus is seated therein, these recesses affording shoulders 15 which bear against the adjacent edge of the flange of the main rail, the portions 13 beyond the main rail containing openings to receive spikes. The guard rail at the side of the body portion thereof next to the main rail is unprovided with a flange as noted, in the case of the guard rail being made from a piece of railway rail this flange being removed, whereby the guard rail may extend in the desired close proximity to the main rail.

In the construction shown, spacer means are provided between the guard rail and the main rail, the means shown in the drawings being of well known construction and involving channel wedge shaped spacers 16 held in place by bolts 17 which pass through one of the legs of the spacer and through the web of the guard rail.

Located between the spacer means 16 are rail braces hereinbefore referred to, these rail braces comprising the plates 9 and wedges 18. The plates 9 are provided with upwardly and inwardly turned ends 19 and 20, the inturned ends 19 forming abutments for a side of the flange of the main rail 5 and the inturned ends 20, which are inclined with respect to the main rail, being provided for cooperation with the adjacent edges of the wedges 18 which extend between them and

the adjacent side of the guard rail 6. The inturned flanges 20 which lap the wedge 18, are engaged at their inclined portions by similarly inclined edges 21 of the wedges 18. The spike openings in the ends of the plates 9 adjacent the wedges 18 extend through the horizontal portions of the flanges 20 and the underlying portions of the plates and also through the ones of the series of openings 22 provided in the wedges 18 which register with the openings in the plates 9.

In the forming of the guard rail from a section of railway rail the ends of the rail are flattened and shaped to produce the portions 13 of the desired shape and size.

The bracing means comprising the plates 9 and wedges 18 operate to resist deflection of the guard rail away from the main rail under the forces exerted against the guard rail when a train travels over the main rail.

In practice it is preferred that the guard rail be so shaped that when it is applied alongside a main rail and interlocked at its ends therewith as shown, but before applying the braces comprising the wedges 18, its body portion will be spaced from the main rail a distance slightly greater than the correct distance, the body portion of the guard rail being moved to the correctly gaged distance by deflecting it toward the main rail by the applying of the wedges 18 to place, the absence of the flange at the inner side of the guard rail as above noted permitting the guard rail to be sprung as desired. When readjustment of the body portion of the guard rail relative to the main rail is desired, as for example in case of wear of wheel-flange-engaging portions of the track structure, such readjustment may be readily made by readjusting the wedges 18 to further deflect the body portion of the guard rail toward the main rail.

It will be understood from the foregoing that a guard rail constructed in accordance with my invention may be readily and quickly installed in place and when installed it is firmly held against lateral displacement relative to the main rail, the particular construction shown providing for adjustment of the guard rail to compensate for wear of wheel-flange-engaging portions of the track structure. Furthermore, it is unnecessary to drill any holes in the main rail or to use any bolts or fittings as hitherto provided for securing the guard rail to the main rail.

The feature of lapping the guard rail by the main rail is of advantage as thereby forces tending to lift the guard rail or rotate it in a direction away from the main rail are effectively resisted, and the provision of the shoulders on the guard rail aid in preventing lateral displacement of the guard rail bodily in a direction away from the main rail.

While I have illustrated and described a particular construction embodying my in-

vention, I do not wish to be understood as intending to limit it thereto as the same may be variously modified and altered without departing from the spirit of my invention.

What I claim as new, and desire to secure by Letters Patent, is:

1. In track construction, the combination of a main rail, a guard rail having a body portion extending alongside said main rail and having end portions extending beneath, and interlocked with, said main rail, and means engaging said body portion and holding it in sprung condition relative to said main rail.

2. In track construction, the combination of a main rail, a guard rail having a body portion extending alongside said main rail and having end portions extending beneath, and interlocked with, said main rail, and adjustable means engaging said body portion and operating, by springing said body portion, to hold the latter in the desired spaced relation to said main rail.

3. In track construction, the combination of a main rail, a guard rail having a body portion extending alongside said main rail and having end portions projecting laterally therefrom and extending beneath said main rail, said body portion being sprung toward said main rail, and means holding said body portion in sprung condition.

4. In track construction, the combination of a main rail, a guard rail having a body portion extending alongside said main rail and having end portions projecting laterally therefrom and extending beneath said main rail, and adjustable means for springing said body portion toward said main rail and holding said body portion in said position.

5. In track construction, the combination of a main rail, a guard rail having a body portion extending alongside said main rail and having end portions projecting laterally therefrom and extending beneath said main rail, spacer means between said main rail and guard rail, and adjustable means engaging the body portion of said guard rail between said spacer means for holding said body portion against movement away from said main rail.

6. In track construction, the combination of a main rail, a guard rail having a body portion extending alongside said main rail and having end portions projecting laterally therefrom and extending beneath said main rail, spacer means between said main rail and guard rail, said body portion being sprung toward said main rail, and means between said spacer means for holding said body portion in sprung condition.

7. In track construction, the combination of a main rail, a guard rail having a body portion extending alongside said main rail and having end portions projecting laterally therefrom and extending beneath said main

5 rail, spacer means between said main rail and guard rail, said body portion being sprung toward said main rail, and adjustable means between said spacer means for holding
5 said body portion in sprung condition.

10 8. In track construction, the combination of a main rail, a guard rail having a body portion extending alongside said main rail, and having end portions extending beneath
10 said main rail, each said end portions having spaced apart abutments located at opposite sides of said main rail, and means engaging said body portion and holding it in sprung condition relative to said main rail.

15 9. In track construction, the combination of a main rail, a guard rail having a body portion extending alongside said main rail means at spaced apart points along said guard rail resisting movement of said guard
20 rail toward said main rail at said points, and means engaging said body portion and holding it in sprung condition toward said main rail between said points relative to said main rail.

25 10. In track construction, the combination of a main rail, a guard rail having a body portion extending alongside said main rail, means at spaced apart points along said guard rail resisting movement of said guard
30 rail toward said main rail at said points, and adjustable means engaging said body portion and operating, by springing said body portion toward said main rail, to hold the latter in the desired spaced relation to said main
35 rail between said points.

40 11. In track construction, the combination of a main rail, a guard rail having a body portion extending alongside said main rail, means at spaced apart points along said
45 guard rail resisting movement of said guard rail toward said main rail at said points, and adjustable means for springing said body portion toward said main rail between said points and holding said body portion in said position.

50 12. In track construction, the combination of a main rail, a guard rail having a body portion extending alongside said main rail and having portions extending beneath said
55 main rail, means at spaced apart points along said guard rail resisting movement of said guard rail toward said main rail at said points, and means engaging said body portion and holding it in sprung condition between
60 said points relative to said main rail.

65 13. In track construction, the combination of a main rail, a guard rail having a body portion extending alongside said main rail and adapted to be sprung, and means engaging
70 said body portion and holding it in sprung condition toward said main rail.

AUGUST ENSTROM.
